SIVERT MOE, OF CHICAGO, ILLINOIS, ASSIGNOR TO THE MIEHLE PRINTING PRESS & MANUFACTURING COMPANY, OF CHICAGO, ILLINOIS, A CORPORATION OF ILLINOIS.

FEED CONTROL AND TRIPPING MECHANISM FOR PRINTING-PRESSES.

1,092,941.

Specification of Letters Patent. Patented Apr. 14, 1914.

Application filed February 29, 1912. Serial No. 680,627.

To all whom it may concern:

Be it known that I, SIVERT Moe, a citizen of the United States, residing at Chicago, in the county of Cook and State of Illinois, 5 have invented certain new and useful Improvements in Feed Control and Tripping Mechanism for Printing-Presses, of which the following is a specification.

My invention pertains to improvements 10 and features of novelty and utility in mechanism for controlling the feed of the sheets of paper to a printing press and for governing the shifting of the impression cylinder onto and off of impression; one object 15 of the invention being to provide a device which will throw the cylinder off of impression and stop the feed of sheets to both of a pair of feed tables when the detector fingers of either table are operated because 20 of an improperly fed sheet on either table, and at the same time preventing further feeding of the sheets from either table to the cylinder until the trouble of the improperly fed sheet has been remedied.

25 In order that a complete and full understanding of this invention may be had, I have illustrated a preferred and desirable embodiment of the same in the accompanying drawings forming a part of this specification, and to which reference should be had in connection with the following detailed description.

In these drawings,—Figure 1 is a fragmentary view, with certain parts omitted, of 35 the mechanism associated with the two feed tables; Fig. 2 is a fragmentary view, with parts omitted showing more or less diagrammatically the cylinder-tripping mechanism operated by the detectors of the feed tables 40 shown in Fig. 1; Fig. 3 is a fragmentary elevation, on an enlarged scale, of the detector mechanism and gripper-operating device associated with one of the feed tables shown in Fig. 1; Fig. 4 is a section on line 4—4 of 45 Fig. 3, showing in fragmentary elevation parts of the sheet-detector mechanism; Fig. 5 is a vertical section on line 5—5 of Fig. 4; Fig. 6 is a partial elevation and partial section, on line 6—6, of the gripper-operating mechanism shown in the left-hand portion of Fig. 3; Fig. 7 is a section on line 50 7—7 of Fig. 3; Fig. 8 is a horizontal section on line 8—8 of Fig. 7; and Fig. 9 is a

vertical section showing the construction of the parts for raising and lowering the feed- 55 roller of one of the tables.

Referring first to Fig. 1, it will be noticed that the machine has a suitable frame 20, in which is journaled the shaft 21 of an impression cylinder 22 adapted to be shifted 60 onto and off of impression by the mechanism illustrated in Fig. 2. The device, as shown in Fig. 1, also includes upper and lower feed tables 23 and 24, respectively, each of such tables being equipped at its 65 right-hand end, as the device is viewed in Fig. 1, with roller means for feeding the sheets singly or individually to the table. In addition, the two tables have associated therewith the transfer cylinders 25 and 26, 70 each supplied with a gripper device 27 and 28, respectively, it being, of course, understood that the impression cylinder 22 referred to above has two oppositely-disposed impression surfaces 29 and 30, each supplied 75 with its paper-holding or gripper mechanism 31 and 32, which are opened and closed at the proper times by mechanism well understood in this art, and consequently not illustrated in these drawings for the sake 80 of clearness of illustration of the remaining parts. A portion of the double form-cylinder 33 which co-operates with the impression cylinder 22 is shown in Fig. 2.

Inasmuch as the two means for advancing the sheets singly from the piles to the tables are substantially alike, a description of one of the same will suffice for both, it being understood, of course, that their operation is so timed by the disposition of their 85 actuating cams that they operate to advance the sheets to the tables in the proper timed relation. On a constantly-driven, transverse shaft 34, a frame or casing 35 is loosely hung or hinged, such frame or casing at its other 90 end having rotatably mounted therein a roller 36 supplied around its periphery with a plurality of smaller rollers 37. Between the shaft 38 of the roller 36 and the shaft 34 there is interposed a series of intermeshing gears 39 carried by the frame or casing 35, the gear at one end being fastened to the shaft 34, the other end gear being fastened to the shaft 38, whereby the revolution 95 of the drive-shaft 34 is transmitted through 100 such gearing to the roller 36. The casing or

frame 35 is connected to an arm 40 (Fig. 9) loosely mounted on a suitably-supported shaft 41 by a link 42, such arm 40 and the roller 36 linked thereto being normally pulled down into paper-engaging position by a coiled contractile spring 43 having one end fastened to the arm 40 and the other end secured to any suitable stationary support. The shaft 41 also has loosely mounted thereon a three-armed member 44, one arm 45 of which bears a roller 46 cooperating with a cam 47 on a suitably driven shaft 48, the driving mechanism of which, for the sake of clearness of illustration, has been omitted. Another arm 49 of the member 44 has pivoted thereto at 50 a small bell-crank lever 51 capable of adjustment with relation to the arm 49 by means of a screw 52 passing through one arm of the bell-crank and cooperating with a lug 53 on the arm 49. The other arm of the bell-crank has a laterally-extended finger 54 projecting beneath the arm 40, so that as the member 44, by the action of the cam 47, rocks around the axis of shaft 41, the arm 40 and the casing or frame 35 will be carried therewith.

When the casing or frame 35 is lowered, which action is permitted during each revolution of the cam 47, the roller 36 comes into contact with the top sheet of the plurality of sheets beneath it and advances such top sheet to the corresponding feed table, and, of course, as soon as the roller 36 is lifted from the pile of sheets, which lifting is brought about during each revolution of the cam 47, no sheet is fed forwardly during such raised condition of the roller.

The feeding mechanism of the top table is also equipped above the shaft 41 with a shaft 55 carrying a finger 56 adapted to be rocked into and out of the path of travel of the remaining arm 57 of the member 44, which is supplied near its end with a notch or recess 58. It should therefore be apparent that if the shaft 55 is rocked so as to swing the projection or finger 56 into the notch 58, then descent of the roller 36 into sheet-engaging position is prevented so long as the finger 56 is held in such lowered position. On this shaft 55 is loosely mounted a handle 59 normally pulled to the left, as viewed in Fig. 1, by a coiled contractile spring 60. The function of this spring 60 is to keep the rod 72 normally elevated, the foot-piece 71 being normally out of engagement with the projection 70. In Fig. 1 the handle 59 and rod 72 are shown in the completed act of depressing the arms 61 and 66 into locking engagement with the hooks 62 and 67, respectively. The shaft 55 has fixed thereto an arm 61, engaging which is the hook end 62 of a lever 63 loosely fulcrumed on the shaft 34 and normally pulled by a spring 64 to cause the hook 62 to engage the arm 61; and when these parts are so engaged, rocking of the

shaft 55 to the left to bring the finger or pin 56 in the path of travel of the arm 58 is prevented.

The shaft 65 of the lower feeding mechanism, corresponding to the shaft 55 of the upper mechanism, has fixed thereto an arm 66, coacting with which is the hook end 67 of a lever 68 fulcrumed on the lower shaft 34 and operated upon by a coiled spring 69. The arm 66 has a rounded projection 70, bearing on the top of which is a foot piece 71 on the bottom end of a rod 72 slidable in a bearing 73. The upper end of rod 72 passes through an apertured block 74 swiveled on an arm 75 constituting a part or lateral extension of the handle 59. The rod 72 has fixed thereto a collar 76, between which and the block 74, and surrounding the rod, is interposed a coiled expansion spring 77, the upper end of the rod protruding beyond the block 74 having pinned thereto a collar 78 limiting the downward movement of the rod.

The arm 61 is provided with an outstanding pin 61' in the downward path of the extension 75 of the handle 59. In practice I preferably employ a spring surrounding the shaft 55 for turning the same, but for the sake of clearness there is illustrated a compression spring 61^a pressing against the under side of the arm 61 and adapted to rock the shaft 55 having the pin 56 when the arm 61 is released from the hook 62. A similar spring 66^a has the same function with respect to the arm 66. It will be seen that when the handle 59 is pulled to the right, as shown in final position in Fig. 1, the extension 75 thereof will have engaged the pin 61^a and forced the arm 61 into engagement with the hook 62, the foot-piece 71 similarly forcing the arm 66 into engagement with the hook 67. On releasing the handle 59, the spring 60 draws the parts 75 and 71 out of engagement with the pin 61' and projection 70, so that when the hooks 62 and 67 are drawn away from the arms 61 and 66 respectively the compression springs 61^a and 66^a are free to rock the shafts 55 and 65 respectively, thus lowering the pins 56 into locking contact with the arms 57.

Leaving the operating mechanism for these paper-feeding rollers 36 for the time being and turning our attention to the detector mechanism, it will be noticed that each feed table is provided with a series of detector fingers, and inasmuch as their construction and that of their operating mechanism are substantially alike, I will describe only that for the upper table. On a suitably supported cross-shaft 79 at the lower end of the feed table 23 (Figs. 1, 3, 4 and 5), a sleeve 80 is loosely mounted, such sleeve having fixed thereto a plurality of depending arms 81, only one of which is shown in Fig. 4, each of such arms having pivoted thereto

a forwardly-extending detector-finger 82, the arm in addition having a projecting pin 83 constituting a stop for the downward swinging of the detector finger. As is well understood in this art, these fingers ride back and forth on top of the sheets, and so long as the sheets are properly fed the detector fingers are inoperative, but if no sheet is fed or a sheet is improperly fed, one or 10 more of the fingers drop into a depression or recess of the tongue over which it slides, so that further forward travel of the detector finger or fingers is temporarily prevented. In order to bring about this constant 15 oscillation of the sleeve 80 and continuous backward and forward travel of the pivoted detector-fingers 82, I fix to the sleeve a bent arm 84, spring-pulled to the right as the parts are viewed in Fig. 3,—that is, to the 20 left as the parts are viewed in Fig. 5—by a coiled contractile spring 85, the upper end of this arm having a substantially semi-circular cavity 86 adapted to accommodate a pin 87 projecting from the side of a pawl 25 88 pivoted at 89 to the upper end of an arm 90 loosely mounted on the shaft 79 and oscillated on such shaft by means of a rod 91 pivoted to the arm at 92, the other end of the rod being pivoted to one end of a lever 30 93 fulcrumed at 94 and carrying at its upper end a roller 95 coating with the face of a cam 96 on the power-driven shaft 48. Between the arm 90 and the bearing 97 of the shaft 79 there is fixed to such shaft a ratchet 35 sector 98, the teeth of which are disposed below the pawl 88, as is clearly illustrated.

As the rod 91 is shifted back and forth by the action of the cam 96, the arm 90 is oscillated on the shaft 79 and the sleeve 80 is oscillated and its detector fingers 82 caused to travel back and forth with the arm 90, being pulled in one direction by the spring 85 as the arm 90 travels in the same direction, and being pulled in the opposite direction against the action of this spring by the arm 90 and the pin 87 in the recess 86 of the bent arm 84. During such oscillation of the parts,—that is, as long as the sheets of paper are properly fed beneath the detector fingers—the pawl 88 does not engage with the ratchet 98, being held elevated away from the teeth of the ratchet by the pin 87 residing in the recess 86. If, however, one of the detector fingers drops into the recess of the tongue beneath it because of the fact that no sheet has been fed or a sheet has been improperly fed, then the travel of the detector finger, the sleeve 80 and the arm 84 is arrested, so that as the arm 90 continues its 50 travel in the same direction, the pin 87 of the pawl passes out of the recess or cavity 86, thereby permitting the pawl 88 to drop into engagement with the teeth of the ratchet 98, the result being that as the arm 90 continues its movement, the shaft 79 to

which the ratchet 98 is fixed turns in the same direction, that is, clockwise as the parts are viewed in Figs. 1 and 3.

By reference to Figs. 3 and 4, it will be noticed that the detector shaft has fixed thereto the two arms 99 and 100, the former having pivoted to its lower end at 101 the left-hand end of a bent rod 102, the right-hand end of which is pivoted at 103 to the lower terminal portion of the lever 63. It should therefore be apparent that when the detector fingers discover that no sheet has been fed or that a sheet has been improperly advanced, the arm 99 swings to the left, carrying with it the rod 102, which in turn rocks the lever 63 so as to uncatch the hook 62 from the arm 61, permitting the shaft 55 to turn in a counter-clockwise direction under the action of the compression spring 61^a to bring the finger 56 into the recess 58 of arm 57, rendering inoperative the paper-feeding function of the roller 36 by preventing its descent into contact with the top sheet of the pile beneath it.

The gripper-operating elements for the cylinder 25 will now be described, reference being had more especially to Figs. 3 and 6. As is customary, the gripper-shaft of this cylinder, as is shown in Fig. 6, is supplied with the usual tumbler 104, which co-operates with two pins or rods 105 and 106 slidably mounted in bearings 107 and 108 on the machine frame. These rods or pins are connected together by a yoke 109, which also has fastened thereto a third or intermediate rod 110 sliding in a bearing 111, this rod being hollow, in part at least, to accommodate and receive a coiled expansion spring 112 in the bearing 111, one end of which bears against the rod and the other end against a plate 113 fixed to the bearing. It should be clear that this spring tends to slide the two tumbler-shifting pins 105 and 106 out of the path of travel of the tumbler. The yoke 109 also has formed as a part thereof an apertured boss 114, slideable in which is a rod 115. This rod or sliding pin 115 is recessed on one side at 116 for the accommodation of the inner end of a retaining screw 117 extended inwardly through the wall of the boss 114, thereby removably but slidably holding the pin or rod 115 in the boss. On one end, rod or pin 115 carries a roller 118 co-operating with the face of a cam 119 attached by means of a screw 120 and centering pin 121 to the end of the shaft 122 on which the cylinder 25 is mounted. This pin 115 has a cavity 123 on one side which receives and accommodates the foot or laterally-extended end 124 of a lever 125 fulcrumed at 126 and acted upon by a spring 127 attached to the lever at one end and to the frame of the machine at the other end. The upper end of lever 125 has pivoted thereto at 128 a hook member 129

hooking over or coating with a pin 130 extended laterally from the arm 90. This hook, near its central portion, has a straight edge 131 adapted for coöperation with the arm 100 disposed directly beneath it. A pin 115^a projects from the side of the machine frame and acts to stop rod or pin 115 from sliding out of action from cam 119 and to prevent member 109 from being pushed in when roller 118 is out of the cam. The operation of this part of the mechanism takes place substantially as follows: The cam 119, being fixedly secured to the shaft 122, rotates therewith, it being understood that the cylinder 25, mounted upon the shaft 122, and the shaft makes two revolutions for each sheet. It should be observed also that the function of the pin or rod 105 is to open the grippers of the cylinder 25, the pin 106 closing the grippers. It will be apparent also that these two pins 105 and 106 will be pushed inwardly into operative relation with the gripper-tumbler 104 only when the roller 118 is pushed up by the foot 124 on lever 125 into coactive relation with the cam face of cam 119. This is brought about, however, only at every other revolution of the feeder cylinder 25. Inasmuch as the pin 130 is fastened to and travels back and forth with the arm 90, which is oscillated by means of the cam 96 and the connecting rod 91, this pin, because of its engagement with the hook 129, will shift the pin or rod 115 and its roller 118 upwardly into operative engagement with the cam each time that the arm 90 is shifted to the right as the parts are viewed in Figs. 1 and 3, and every time that this is brought about the pins 105 and 106 will be pushed inwardly into the path of travel of the gripper-tumbler. Obviously, if it is desired to prevent the gripping of a sheet improperly advanced to the gages on the feeder table, this may be done by causing the detector fingers to prevent the inward sliding of the tumbler-actuating pin 106, which operation would, of course, prevent the grippers from closing and prevent the cylinder from taking a sheet from the feed table. This connection between the detector fingers and the grippers operates as follows: As has been noted above, when the detector fingers discover that a sheet has been improperly advanced on the feed table, the arm 100 swings to the right as the parts are viewed in Fig. 3, and in so doing its end rides under the surface 131, raising the hook 129 out of engagement with the pin 130, that is, this movement of the parts breaks the connection between the arm 90 and the lever 125, so that the movement of the former is not transmitted to the latter and the pin 115, the latter being retained in depressed position with its roller out of engagement with cam 119, the result being

that neither of the pins 105—106 is pushed into tumbler-engaging position. This inaction of the pins 105 and 106 will continue so long as the arm 109 is maintained in elevated position, which will be as long as the detector fingers discover trouble in the registration of the sheet of paper with the gages, or discover that no sheet at all has been fed. Consequently, an improperly-fed sheet will be retained on the table until it is properly registered with the gages, for the reason that the grippers of the cylinder 25 will not take it away. 75

It is one of the objects of this invention to stop the feeding on both tables if the detector fingers of either discover that no sheet has been fed or that one has been fed incorrectly, and in order to establish this connection between the two detector mechanisms, or, viewed in another light, between the two cylinders 25 and 26, the following parts are employed: At the side of the machine I rotatably mount in a pair of bearings 132 and 133 an upright shaft 134 (Figs. 1, 3, 7 and 8), and on this shaft are fixed upper and lower sectors 135 and 136, each equipped with a substantially central notch or recess 137, and in addition the shaft has fixed thereto a locking ratchet or notched member 138, with which coacts a spring tongue 139 adapted to ride over the projection between the notches and hold the shaft in either one of two positions. As has been explained hereinabove, when the detector fingers act, the rod 102 is shifted to the left as the parts are viewed in Figs. 1 and 8, and each of these rods (that is, two for the upper and lower tables) has fastened thereto a block 140, pivoted to which is a finger or arm 141 carrying an upwardly-extended pin 142, such arm being pressed toward the frame of the machine, that is, toward the corresponding sector 135 or 136, by a leaf spring 143. Each detector mechanism has the hub 144 of its bent arm 84 supplied with a side projection 145, it being remembered that the hub 144 is either integral with or fixed to the sleeve 80, and the vertical shaft 134 has fastened thereto two arms 146 and 147 adapted to be swung simultaneously into the path of travel of the two projections 145, as is perhaps more clearly illustrated in Figs. 1, 3, 7 and 8. When, for example, the detector fingers of the upper feed-tables are arrested in their movement, that is, detect or discover an improperly-fed sheet, the rod 102 shifts to the left, and, in so traveling, the projection 142 on the spring-pressed arm 141 passes into the notch 137 and acts through the sector 136 to rock the shaft 134 so as to bring both of the arms 146 and 147 into the plane of their coacting arms 145. Assuming that the fingers of the upper feed-table have detected a sheet improperly fed, this swinging of the arm 147 into the path of 100 105 110 115 120 125 130

travel of the projection 145 prevents the detector fingers of the lower feed-table from traveling back and forth in the normal manner. In other words, it holds them back just as though their ends had dropped into the recesses of the tongues over which they slide, the result being the same as though the lower detector-fingers had been held back in their movement by the discovery or detection of the failure of a sheet to be fed, or of an improperly-fed sheet. This brings about the disengagement of the hook 129 from the pin 130 of the lower detector mechanism, which results in rendering the gripper fingers of the lower cylinder 26 inoperative to feed the sheet to the cylinder 22. If, on the other hand, the fingers of the lower feed-table had discovered an improperly-placed sheet, the movement of the shaft 134 would bring the arm 146 under the projection 145 and prevent further feeding of sheets from the upper table, so that if the feeding is not proper on either table the feeding is stopped from both tables, and at the same time, owing to the movement of the rods 102, the feeding of the sheets from the piles upon the two tables is stopped, the two hooks 62 and 67 being moved, as has been described above, so as to prevent the descent of the rollers 36 into paper-engaging position. Consequently no sheets will be fed to the tables and no sheets will be fed from the tables to the cylinders 25 and 26 until the cause of the trouble has been removed, and then to start the mechanism into operation again it is necessary for the person having the machine in charge to shift the handle 59 to the right as the parts are viewed in Fig. 1, so as to cause an engagement of the hooks 62 and 67 with their coacting parts to maintain the fingers 56 in elevated position. Since this hooking engagement for the two hooks cannot occur simultaneously, the sliding connection between the rod 72 and the block 74 is provided. When the two rods 102 shift to the right, they move their sectors 135 and 136 in the same direction by means of the arms 141, and rock the shaft 134 and arms 146 and 147 into normal inoperative position.

When the detector fingers act because of the discovery of an improperly-fed sheet, it is desirable to throw the impression cylinder off of impression, regardless of whether the improperly-fed sheet is on one table or the other, or two sheets improperly advanced onto the feed tables simultaneously. To accomplish this result I employ the mechanism illustrated in Fig. 2, which is located at the opposite side of the machine from that part of the construction shown in the other figures. Each bearing block 150 for the shaft of the impression cylinder 22 is slidably mounted in the frame of the machine toward and away from the form cylinder 33 by

means of a slightly eccentric shaft 151 between which and the corresponding bearing block 150 there is interposed a saddle 152; this shaft having also, integral therewith or fixed thereto, an arm 153 connected by a link 154 to one arm 155 of a double-armed member 156 fulcrumed at 157, the other arm 158 of such member having pivoted thereon at 159 a double-ended pawl 160. Also oscillatory about the center 157 I use a notched or ratchet member 156^a provided on its periphery with a recess having at its ends the two oppositely-facing shoulders 161 and 162, a projecting arm 163 of the member 156^a carrying a roller 164 traveling in a cam groove 165 of a suitably rotated cam 166 geared in any approved manner to the operating mechanism of the press so as to revolve about its axis 167 one revolution for each half revolution of the double impression cylinder 22.

In order to oscillate the shaft 159 having fixed thereto the double-ended pawl 160 so as to obtain an operative connection to throw the impression cylinder off of and on to impression, I employ in combination the following elements: At 168 I fulcrum a lever 169 counterweighted at 170 and provided with a notched projection 171 cooperating with which is a fixed leaf spring 172 to hold the lever in either one of two positions. A rod 173 is pivoted to the lever 169 at 174 and extends through an apertured boss 175 on an arm 176 fast on shaft 159. Fixed to the rod I use two collars 177 and 178, and employ between the collars and the boss 175 the two coiled expansion springs 179 and 180, which act normally to center the pawl 160, holding both of its ends out of engagement with the two shoulders 161 and 162 of the constantly-oscillating member 156^a actuated by the cam 166. At 181, I pivot to the lever 169 a longer and a shorter fork 182 and 183, respectively, each having at its upper end the parallel tines or arms 184 and 185, the former being equipped with a shoulder 186 facing upwardly, while the latter is supplied with a shoulder 187 facing downwardly. The upper fork 182 is rendered capable of lateral shifting or swinging around its point of support 181 by means of a link 188 pivoted to the fork at 189, and at 190 to an arm 191 fixed on the upper detector shaft 79. The lower fork 183 is correspondingly associated and connected to an arm 192 fastened to the lower detector shaft 79 by means of a similar link 193. The shaft 21 of the impression cylinder 22 carries a cam 194 having in its face a cam groove 195, and pivoted to any suitable support at 196 a bell crank 197 is used, one arm of which has a roller 198 traveling in the cam groove 195, while the other arm has pivoted at 199 a pawl or dog 200 equipped at its opposite sides with oppositely-facing 125

teeth or shoulders 201 and 202 in the vertical plane of the fork 182, this pawl or dog being normally held in central position by a bowed leaf-spring 203. Also the construction contemplates the employment of a larger bell crank 204 fulcrumed at 205, one arm of the same having a roller 206 coöperating with the cam slot 195, the other arm having a spring-controlled pawl 207 with 10 the opposite teeth or shoulders 208 and 209, such pawl being adapted for direct association with the upper bifurcated end of the fork 183, as is clearly illustrated in Fig. 2.

If the detector fingers 82 of the upper table discover or detect the fact that a sheet of paper has been improperly fed or no sheet has been advanced when it should have been fed, the movement of such fingers will be arrested, as has been explained above, bringing about the oscillation of the upper detector shaft 79 and the swinging of the arm 191 in the counter-clockwise direction as the parts are viewed in Fig. 2. The result of this action is that, through the instrumentality of the connecting link 188, the fork 182 is swung to the left, bringing the shoulder 187 into the path of travel of the tooth or shoulder 202, which is constantly reciprocated up and down because of the rocking 25 of the bell crank on which it is mounted by the cam groove 195. During the upward stroke or travel of the pawl 200, under these circumstances, its shoulder or tooth 202 engages the shoulder 187, carrying the fork 182 upwardly with the pawl, which, of course, swings the lever 169 on its fulcrum 168, pushing the rod 173 toward the right. Such movement of the rod oscillates the pawl 160 bringing its left-hand end into the path 30 of travel of the shoulder 162, and as soon as such shoulder engages the pawl, it being understood that the member 156 on which the shoulder 162 is formed is constantly oscillated by the cam 165, the double-armed member 156 will be swung to the right, the link 154 will be pushed up, the shaft 153 will be rocked, and the bearings of the shaft 21 on which the impression cylinder is mounted will be lowered, shifting the impression cylinder into off-impression position. The cylinder will stay off of impression until the defect in the feeding of the sheets of paper has been remedied, and when this occurs the arm 191 will rock to the right, 45 and by means of link 188 will push the shoulder 186 into the path of travel of the tooth or shoulder 201, and when the pawl 200 descends by the coöperation of these two shoulders, the fork 182 will be pushed down, 50 rocking the lever 169 around its fulcrum against the action of the counterweight 170, which movement will swing the other end of the double pawl 160 into the field of action or path of travel of the shoulder 161, and

when these parts engage one another, the 65 rocking member 158 in its movement will shift the double-armed member 156 back to original position, which, of course, means the moving of the impression cylinder again onto impression. When this has occurred 70 the double-armed pawl 160 will automatically assume neutral or normal position under the action of the two springs 179 and 180, as shown in Fig. 2. The spring 172 is adapted to hold the lever 169 either in the 75 normal position shown in Fig. 2, with the cylinder on impression, or in the position of the parts assumed when the cylinder is off of impression. From the above it should be quite clear that a corresponding action 80 will take place if the detector fingers of the lower table discover an improperly-fed sheet, so that if either detector mechanism is operated, the cylinder will be thrown off of impression and maintained off of impression until the defect in the feeding is remedied.

It should be apparent from the above that if the detector fingers of either detector mechanism engage the recesses of the tongues 90 beneath them because a sheet is improperly fed to the gages, or due to the fact that no sheet is fed, then the other detector mechanism will be similarly operated through the medium of the shaft 184 and associated 95 parts. Also the gripper operating mechanisms of both of the transfer cylinders 25 and 26, which feed the sheets from the tables to the common impression cylinder, will be unclutched from their actuating mechanism, so that no sheets will be gripped by either of these cylinders. Furthermore, both rollers 36 of the two tables will be rendered inoperative to feed sheets from the piles to the corresponding tables, and the 100 impression cylinder will be thrown off of impression and maintained off of impression until the trouble with the feeding has been remedied and the machine again set into operation by the manipulation of the handle 59. 110

While I have herein set forth and described with some degree of particularity the features of construction and operation of a preferred and desirable embodiment of the invention, it should be understood that the latter is not limited and restricted to these precise and exact details, because the invention is susceptible of embodiment in many different forms, and the mechanical features of the device herein described may be varied within wide limits without departure from the substance of the invention. 115

I claim:

1. In a printing press, the combination with an impression cylinder of a plurality of feed tables therefor, a detector for each table, and means to actuate one of said detectors so as to stop feeding without stop- 125

ping the press when the other detects a defect in the feeding of its sheets, substantially as described.

2. In a printing press, the combination 5 with an impression cylinder of a pair of feed tables therefor, a detector for each table, and a connection between the detectors whereby to actuate the companion detector so as to stop feeding without stopping the 10 press when either of the detectors detects a defect in the feeding of its sheets of paper, substantially as described.

3. In a printing press, the combination of 15 a plurality of feed tables, detector fingers for each of said tables, means to reciprocate said detector fingers, means to arrest the movement of said detector fingers if the feeding of the sheets of paper thereto is defective, and means to arrest the movement 20 of the detector fingers of all of the remaining tables if the detector fingers of any table are arrested in their movement because of improper sheet feeding, substantially as described.

25 4. In a printing press, the combination with an impression cylinder of a plurality of feed tables therefor, means to remove the sheets from each of said tables, a detector for each of said tables, and means connecting 30 the several detectors whereby to render all

of said paper-removing means inoperative without stopping the press when any of said detectors discovers a defect in the feeding of its sheets of paper, substantially as described.

35

5. In a printing press, the combination of a pair of feed tables, a feed cylinder for each of said tables to remove the sheets therefrom, a detector for each of said tables, and means to render both of said feed cylinders 40 inoperative if either detector discovers a defect in the feeding of its sheets of paper, substantially as described.

6. In a printing press, the combination of 45 an impression cylinder, a plurality of feed tables, a feed cylinder for each of said tables to remove the sheets therefrom and deliver them to said cylinder, means to feed sheets of paper to each of said tables, a detector for each of said tables, and means to 50 trip said cylinder off of impression and to render all of said feed cylinders and means to feed the sheets to said tables inoperative if any of the detectors discovers a defect in the feeding of its sheets of paper, substantially as described.
